ATTORNEY

UNITED STATES PATENT OFFICE.

JOE J. BARTOLI, OF STOCKTON, CALIFORNIA.

EMERGENCY FUEL, OIL, AND WATER ATTACHMENT FOR MOTOR VEHICLES.

1,405,089.

Specification of Letters Patent. Patented Jan. 31, 1922.

Application filed May 13, 1921. Serial No. 469,331.

To all whom it may concern:

Be it known that I, JOE J. BARTOLI, a citizen of the United States, residing at Stockton, county of San Joaquin, State of California, have invented certain new and useful Improvements in Emergency Fuel, Oil, and Water Attachments for Motor Vehicles; and I do declare the following to be a full, clear, and exact description of the same, reference being had to the accompanying drawings, and to the characters of reference marked thereon, which form a part of this application.

This invention relates to improvements in devices for providing emergency supplies of the three essentials necessary in the operation of motor cars, namely, fuel, oil, and water, the principal object of my invention being to provide a device in the form of a tank to contain the three liquids mentioned, and a system of piping leading from the tank to the various permanent supplies the control valve for each fluid being located within easy reach of the driver of the car from his seat.

Another object is to provide for air pressure means to constantly act on the emergency supplies, so that the tank containing the same may be located anywhere on the car, with the assurance that the liquids, when the control valves are opened, will flow to their respective points to replenish the depleted supplies of the engine.

A further object is to provide a system of this character in which the only parts which need be visible are the control valves and the parts immediately adjacent thereto.

The advantages of such a system are thought to be obvious, but will be pointed out briefly, the only necessity for its successful operation being of course to see that the tank is filled and the pressure acting thereon before starting on a trip.

Besides the carelessness or thoughtlessness of some people which renders them liable to start out without seeing to their supplies, there is always the possibility of a leak developing on the way, and which may cause the rapid exhaustion of any one of the vital fluids mentioned.

No one can foresee such an occurrence, nor can the leaks usually be repaired on the road, so that without an emergency supply such as I provide, the engine may overheat, or the bearings freeze and become ruined through

lack of oil, or if the gasoline is exhausted, the car must be towed to the nearest supply station.

A further object of the invention is to produce a simple and inexpensive device and yet one which will be exceedingly effective for the purposes which it is designed.

These objects I accomplish by means of such structure and relative arrangement of parts as will fully appear by a perusal of the following specification and claims.

In the drawings similar characters of reference indicate corresponding parts in the several views.

Fig. 1 is a side elevation in outline of a motor car, showing my improved system installed thereon.

Fig. 2 is top plan view thereof.

Fig. 3 is a sectional view of the emergency-supply tank.

Referring now more particularly to the characters of reference on the drawings, the numeral 1 denotes a suitably sized tank, which may be installed under the rear seat of the car, or any place where it is not in the way, and yet is readily accessible.

The tank is divided by partitions 2 into compartments 3, 4, 5 and 6, for oil, gasoline, water and air, though of course in the case of an air cooled car (such as the Franklin) the water compartment is omitted.

The compartments may be varied in size and to suit requirements, as it will be evident that the car will not need as large a supply of oil for instance as it does gasoline, nor yet as much water. I have therefore shown the gasoline compartment as being the largest, though of course the proportions as to size may be varied, as may be desired.

The liquid compartments are fitted with filler-caps or plugs 7 while the air chamber 6 has an air valve 8, of the kind used on tires, so that an air pump may be attached thereto.

A common passageway or bypass 9 leads from the air chamber to the liquid compartments on top thereof and communicates therewith through openings 10, each such opening having a flap-valve 11 opening downwardly, so that air pressure in any compartment cannot back up into the chamber 6, nor can any liquid spill from one compartment into another with the jolting of the car.

Pipes 12, 13 and 14 lead from the bottom of the oil, gasoline and water compartments

respectively to the crank-case or sump 15, gas tank 16 and radiator 17 respectively, these pipes being preferably of the flexible seamless variety, so that they may be bent 5 as necessary to pass around fixed parts of the car without interfering therewith.

These pipes preferably extend vertically and alongside each other adjacent the dash board of the car, in order to interpose sight-10 feed glasses 18 therein, above which are control valves 19 within reach of the driver of the car.

The purpose of the glasses is to enable 15 the operator to tell at a glance whether the fluid is flowing through any pipe when its valve is opened, as otherwise he would have no means of knowing when the emergency supply had been drained, and would be merely taking air under pressure through 20 said pipe, which is not only undesirable but would quickly exhaust the air pressure.

The air in the chamber 6 is compressed to whatever degree is necessary to cause the fluids to flow freely to any part of the car, 25 without depending on gravity, so that the tank may be located at a point considerably lower than the points of discharge of the fluids into their respective reservoirs.

A gauge 20 may be fitted onto the chamber 30 6 to determine the pressure attained.

From the foregoing description it will be readily seen that I have produced such a device as substantially fulfills the objects of the invention as set forth herein.

35 While this specification sets forth in detail the present and preferred construction of the device still in practice such deviations from such detail may be resorted to as do not form a departure from the spirit of 40 the invention, as defined by the appended claims.

Having thus described my invention, what I claim as new and useful and desire to secure by Letters Patent, is:—

45 1. An emergency liquid-supply system for motor cars including a tank divided into a plurality of independent compartments, one for each liquid and one for air, the latter being adapted to hold air under pressure, and 50 means whereby the air therein may pass into

all the compartments but the liquids therein cannot communicate with each other.

2. An emergency fluid-supply system for motor cars comprising independent sources of emergency supply maintained under pressure, a pipe leading from each such supply to the permanent respective reservoir of the car, a control valve for each pipe, and a sight-feed glass in each pipe adjacent the corresponding valve. 55

3. An emergency liquid-supply system for motor cars, including a tank divided into a plurality of independent compartments, one for each liquid and one for air, the latter being adapted to hold air under pressure, 60 and means whereby the air pressure in the above compartment will be distributed equally to the liquid compartments.

4. An emergency liquid-supply system for motor cars including a tank divided into 70 independent compartments, one for each liquid, and one for air, means for admitting air into said latter compartment and maintaining it therein under pressure, a common passageway from the air compartment 75 to the fluid compartments, a pipe leading from each of the latter compartments to the corresponding permanent reservoir of the engine, and control means for each pipe positioned within reach of the driver of the car 80 from his seat thereon.

5. An emergency liquid-supply system for motor cars including a tank divided into a plurality of independent compartments, one for each liquid; and an air pressure chamber 85 provided with the tank and communicating with all the liquid compartments.

6. An emergency liquid-supply system for motor cars including a tank divided into a plurality of independent compartments, one for each liquid and one for air, the latter being adapted to hold air under pressure, a common passageway from the air compartment to the fluid compartments, and valves 90 opening inwardly of the compartments interposed between the latter and the passageway. 95

In testimony hereof I affix my signature.

JOE J. BARTOLI.
